UNITED STATES PATENT OFFICE.

EUGENE M. BOURNONVILLE, OF JERSEY CITY, NEW JERSEY.

ROTARY VALVE.

Application filed February 15, 1923. Serial No. 619,112.

To all whom it may concern:

Be it known that I, EUGENE M. BOURNONVILLE, a citizen of the United States, and a resident of Jersey City, in the county of Hudson and State of New Jersey, have invented certain new and useful Improvements in Rotary Valves, of which the following is a specification.

The invention relates to rotary valves, and particularly to internal combustion engines having rotary valves controlling the intake and exhaust of the gases. The object of the invention is to provide certain improvements upon and within the patent to Carlisle For-
rest Smith, No. 1,442,705 of January 16, 1923, as hereinafter more particularly pointed out and claimed.

In the accompanying drawings forming part hereof:

Fig. 1 is a vertical transverse section through the valve mechanism and the upper part of one of the cylinders of a multi-cylinder internal combustion engine;

Fig. 2 is a central longitudinal vertical section taking in two of the engine cylinders and one complete valve member section; and

Fig. 3 is a bottom plan of the wedge member.

The numeral 1 designates a cylinder block, and 2 a separate head, the parting or joint being marked 3. The engine will be understood as comprising a plurality of cylinders, of which the one in the plane of the section is marked 4. The head and the adjoining portion of the cylinder block together form a casing for a rotary cylindrical valve member or plug 5, which extends longitudinally over the tops of the cylinders, preferably in two or more flexibly jointed sections as is familiar.

The valve casing contains an incomplete cylindrical bore 6, at the bottom of which is a port communication 7 to the combustion chamber 8 of the cylinder, while at opposite sides are an intake manifold and port 9, 10 and an exhaust port and passage 11, 12. The cylindrical bore curvature forms seats between at the sides of these several ports and may extend above the central horizontal plane of the valve member, though at the intake side the bore is preferably relieved above the intake port as shown at 6^a. The valve member is formed with pocket ports 13 in its sides which are properly positioned to connect the cylinder port 7 alternately with

the intake and the exhaust at the proper times. The valve is suitably connected with the crank-shaft to rotate always in one direction, the direction of rotation being indicated by the arrow.

The portion 14 of the valve chamber above the fixed bore and opposite the port 7 is formed to accommodate a shoe 15, or mobile part of the casing, having a segmental under face substantially conforming to a considerable portion of the cylindrical surface of the valve member, it being understood, of course, that the curvature of the shoe like that of any bearing is of somewhat greater radius than the rotating member. Above, that is to say, back of, the shoe, at the top of the chamber 14 is a straight transverse, inclined, rigid way or slide surface 18, against which the shoe is supported through the intermediary of a slide or wedge 16 having a sloping back 17 affording an extended sliding surface, the slope or taper being transverse to the shoe and valve and contrary to the direction of rotation of the valve member and being at a low angle to the line or tangent which is at right angles to the central line passing through the port 7, the center of the valve member and through or near a rocker joint or point of tilting support, the present preferred form of which will now be described.

The back of the shoe is provided with a plurality of rounded teeth or projections 19 alternating with a curved gullet or gullets disposed in transverse series, these elements being arranged on an arc substantially concentric with the curved face of the shoe. As seen in Fig. 2, these formations need not extend the full length of the shoe, but may be confined to a rib 43 projecting from the back of the shoe intermediate its ends. The slide or wedge 16 is formed in its under face with a series of corresponding teeth and gullets 19^a arranged in a straight line substantially normal to the aforesaid central line, somewhat after the fashion of a rack. The slide and shoe are urged in the direction of the taper, and contrary to the direction of rotation of the valve member, by a spring 20 in a spring chamber 21 bearing against the broad end of the wedge.

The spring means opposes the circumferential movement of the shoe in one direction and presses the shoe against the valve member and the latter to its seat in the fixed bore, so as constantly to hold the valve tight.

irrespective of expansion and contraction or wear. The slope of the wedge and wedge-way is too low to permit the wedge to yield to the force of the explosions or of the compression or the exhaust, the wedge being self-holding in this respect. If, however, the valve tends to stick owing to expansion, the increased frictional drag of the valve member on the shoe transmitted through the articulation or toggle forces the parts slightly against the springs and thereby automatically relieves the condition. Slight radial movement of the shoe, in or out with respect to the center of the valve, is thus obtained by virtue of true circumferential movement in one direction or the other. The springs are of such strength as to resist normal frictional drag sufficiently to secure the desired tightness.

The function of the plurality of teeth and gullets on the members of the movable two-part compensating structure is to provide a multiple articulation for these parts, permitting transverse rocking of the shoe, instead of the single articulation of the Smith patent. An advantage of such a construction is that it keeps the central point of support of the shoe always substantially in one place at or near the central line, which can be readily understood by conceiving of the wedge as a rack and the toothed shoe as a pinion oscillatable about the axis of the valve member. It will be understood that there need not be as many teeth and gullets as shown, and the teeth may be smaller and nearer together.

In the particular condition shown in Fig. 1 the upward pressure on the valve is being transmitted from the bottom of the central gullet of the shoe to the corresponding tooth of the wedge. If the wedge moves sufficiently to the right the point of pressure will be between the tooth of the shoe at the left of the central gullet and the corresponding gullet of the wedge, while if the wedge moves sufficiently to the left the point of pressure will be at the tip of the tooth next to the right on the shoe. While the actual range of movement is slight, the construction is of advantage because it requires less accuracy in manufacture because there is no possibility of the wedge moving to the right so far that the shoe is no longer forced inward but is permitted to recede, which would result in the parts becoming locked against return.

The wedge and its wedge-way may otherwise be constructed substantially as shown in the Smith patent, or it may be made as shown in the accompanying drawings in the form of a pin or bar having a back and sides of cylindrical curvature to fit a correspondingly curved slideway in the casing. This form of the wedge or slide is simple and inex-

pensive and permits the member to rock upon its longitudinal axis, that is to say an axis transverse to the valve member, which in turn permits the shoe to have freedom for tilting or rocking in the longitudinal sense in addition to its capacity for transverse tilting. The advantages of such universal support for the shoe, movable circumferentially under the drag of the valve member, are set forth in an application of Carlisle Forrest Smith of even date herewith.

Another feature of the invention has to do with the division of the shoe element of the valve longitudinally of the valve member into a plurality of shoes, of which, as shown in Fig. 2, there are two for each section of the valve member which spans two cylinders of the engine, there being according to this arrangement one shoe and a corresponding wedge and spring for each engine cylinder, though this may be modified. This subdivision of the shoes relative to the sections of the valve member permits each independent shoe to move a different distance circumferentially of the valve in the operation of the compensating device. In this way there is taken into account variations in manufacture through which the valve section may be slightly larger toward one end than the other and other variations having similar effects. In these rotary valve engines with their high temperatures the requirements of bearing and seal at the various regions are exceedingly exacting, and it is therefore a matter of great actual importance to secure at all times and in all places exact adjustment in operation, and at the same time to avoid the necessity for such high degree of accuracy in manufacture as to render their cost excessive. The described sectioning of the shoe contributes in substantial measure to these results and likewise toward rendering the parts interchangeable.

While the preferred form of the invention has been described in detail it will be understood that I do not limit myself to the precise construction illustrated and that various changes and reversals may be made without departing from essentials.

What I claim as new is:

1. In a multicylinder internal combustion engine, a rotary valve casing extending lengthwise of the series of cylinders, a rotary valve member section therein, a plurality of compensating shoes bearing upon different portions lengthwise of the valve section, said shoes being independently movable circumferentially of the valve section, independent slide members to which the respective shoes are flexibly articulated, and springs urging said slide members and shoes in opposition to the drag of the different portions of the valve section.

2. In a rotary valve having a rotary valve member, and a casing, an automatic compensating device comprising a shoe movable circumferentially on the valve member and a transverse slide member to which said shoe is articulated for transverse rocking movement, said slide member in turn being capable of rocking crosswise to the rocking thereon of the shoe.
3. In a rotary valve having a rotary valve member, and a casing provided with a transversely inclined guide, a spring-pressed member slideable on said guide transversely of the valve member and rockable in the guide, and a shoe articulated to the slideable member and movable circumferentially on the valve member.
4. In a rotary valve having a rotary valve member, and a casing provided with a transversely inclined guide, a spring-pressed member slideable on said guide transversely of the valve member and rockable in the guide, said slideable member having a plurality of teeth, and a shoe movable circumferentially on the valve member and having a plurality of teeth to mesh with those of the slideable member.
5. In a rotary valve, a valve member, a casing having a transverse guide channel, a spring-pressed toothed bar mounted to slide and to have slight turning movement in said guide channel, and a shoe having teeth to mesh with the teeth of the bar.
6. In a rotary valve, having a rotary valve member and a casing, an automatic compensating device comprising a shoe movable circumferentially on the valve member, and a slideable member backing the shoe, said shoe and slideable member having multiple articulating elements.
7. In a rotary valve, having a rotary valve member and a casing, an automatic compensating device comprising a shoe movable circumferentially on the valve member and having teeth at its back arranged on an arc, and a transversely slideable member having rack teeth to engage the teeth of the shoe.
8. In a rotary valve, having a rotary valve member and a casing, an automatic compensating device comprising a shoe movable circumferentially on the valve member and having a plurality of teeth at its back arranged on an arc, and a spring-pressed wedge member having an inclined back guided transversely in the casing and teeth on its opposite side to mesh with the teeth on the shoe.
9. In a valve, the combination with a rotary valve element, of a plurality of compensating devices cooperating with different portions lengthwise of said valve element, said devices comprising shoes movable independently circumferentially of the valve element, and means whereby the circumferential movement of the shoes occasions slight recession or approach thereof with relation to the center.

EUGENE M. BOURNONVILLE.
